BUTTON FASTENER

Arthur Illsche, Rye, N. Y.

Application March 26, 1937, Serial No. 133,110

1 Claim. (Cl. 24—105)

The present invention relates to a fastener for detachably securing any well known type of button, ornament or the like to a fabric, in a manner to permit ready removal and replacement, whenever desired. The broad idea of the fastener is disclosed in my prior Patent No. 2,075,722, issued March 30, 1937, and the present application is a continuation, in part of the application on which the above patent was granted.

As disclosed in my prior patent referred to, the primary purpose and object of the invention is to provide a fastener for detachably securing buttons, ornaments and the like, of the "sew-on" type, to a fabric. The fastener consists of two members, arranged ordinarily one on each side of the fabric and screw-threaded for connection through the fabric, without puncturing the same. The fastener member on the outside of the fabric is attached to the button and the method described for effecting attachment, is to sew the member to the button, which may then be detachably secured at any place desired on a garment or other fabric, by screwing the inner fastener member on the outer button member, through the intervening fabric.

While sewing is a convenient method of attaching the button or other article to the outer fastener member, a thread tie or binder has limited life as the thread stretches, wears and eventually breaks and for that reason, a stronger and more lasting form of attachment is desirable, such, for example, as cement or any other strong and lasting adhesive, which will serve to bind the button securely to the outer member of the fastener.

While cement or its equivalent would serve alone, both cement and thread can be used to advantage, as the thread will tie and hold the button and fastener member together in centered relation, until the cement sets or hardens, to make the connection permanent.

A cement or equivalent binder has many advantages over a thread tie and serves the same purpose, as it enables women to make all buttons, ornaments, trimmings, etc., sewed fast to their garments, readily removable and replaceable, for purposes of laundering, cleaning or remodeling the garments and saves the labor and wear and tear on the fabrics involved in the present practice of cutting off the buttons, etc., and sewing them on again, after garments have been washed, cleaned or re-made.

A cement or equivalent binder has a more extensive use than a thread tie, as it can be applied, regardless of whether the buttons or other articles are of the "sew-on" type or not, thereby

including many metal and other ornaments which lack thread openings.

In applying cement, the operation is very simple and requires neither skill nor experience, as it is only necessary to put a drop of the cement on or in the upper end of the outer fastener member and another drop on the underside of the button, ornament or other article, press the two together for a moment and then let them stand until the cement hardens.

In the accompanying drawing, I have shown a number of the more important uses of the invention but do not wish to be understood as intending to limit myself to the same, as it will be apparent that the invention may be applied to many other articles used in connection with fabrics of various kinds.

In the drawing—

Fig. 1 is a view, partly in elevation and partly in section, greatly enlarged and exaggerated for clearness of illustration, showing the invention applied to a "sew-on" type of button, ornament or the like. In this view, both thread and cement are employed to secure the button to the outer member of the fastener.

Fig. 2 is a similar view, showing the application of a slightly modified form of the invention to an ornament or other article, indicated diagrammatically by a rectangle, lacking thread openings and secured by cement alone.

Fig. 3 is a view in perspective of the inner member of the fastener.

Fig. 4 is a similar view of a slightly modified form of the same.

Fig. 5 is a sectional view, showing a further modification, and

Fig. 6 shows the fastener members rearranged to stand outward from the surface of the fabric, to avoid the projection on the inner side thereof, as in Fig. 1.

Referring now to the drawing, 1 represents the fabric, 2 the button ornament or the like and 3 and 4 are members of the fastener by which the button, ornament or the like, is detachably secured to the fabric. The fastener member 3, shown on the outside of the fabric, will hereinafter be termed the outer member and the fastener member 4, shown in Figs. 1 and 6, on the inside of the fabric, will hereinafter be termed the inner member.

The outer member 3 may be made in the form of a frusto-conical shell, as shown in Figs. 1 and 6, or of the same exterior form but solid and recessed at its upper end, and is shown thus modified in Fig. 2. Aside from the difference mentioned,

the members 3, shown in Figs. 1 and 2, are substantially identical.

To enable either form to be sewed to a button, ornament or the like, as disclosed in my prior 5 patent, above referred to, a number of suitably disposed openings 5, 5, etc., are provided therein for the passage of thread, indicated at 6, in Fig. 1.

In the preferred embodiment of the invention, if the outer fastener member is sewed to the 10 button, the thread merely serves to tie the two together temporarily or until the cement or its equivalent, introduced between them, as indicated at 7, sets or hardens and makes the connection permanent.

15 As the body of the outer fastener member is made of a size not larger than is necessary to encircle and enclose the thread opening formation of the ordinary button, a drop or two of cement or its equivalent, in or on the upper end of the 20 fastener member, will be sufficient to secure it to the button. To steady the fastener member on the button and give added strength to the cement joint formed, the member is preferably provided at its upper end with a flange 8, which extends the 25 contact surface of the member and the intervening layer of cement against the under side of the button, as shown.

While cement and thread, as here employed, are merely different forms of attaching means 30 and serve the same purpose, in enabling women to make the buttons, ornaments and the like, in use on their dresses, readily removable and replaceable, without damaging the fabric, the one (cement) is quickly and easily applied and is thereafter lasting and permanent, while the other (thread) involves considerable time and labor and is then only temporary, requiring renewal from time to time.

35 As in my prior patent referred to, the members of the fastener are designed to be connected 40 through the fabric, without piercing or puncturing the same and for this purpose are screw-threaded as indicated at 9.

Again, as disclosed in the patent referred to, the fastener members are given a frustro-conical shape to make the screw-thread connection effective through fabrics of different thickness.

The inner fastener member 4 may be given an 5 external body shape suitable for engagement by a small socket wrench (not shown), as indicated at 10 in Fig. 3, or it may be modified to have an upper flange 11, thus shaped, as shown in Fig. 4. The use of a wrench is not ordinarily 10 necessary but, if used, gives added security by bringing the fastener members into closer relation than is possible by a thumb and finger grip.

The inner member 4 as shown, may be open or 15 closed at the bottom excepting when used to secure fabrics, such as tapestries, portières, etc., to the walls of woodwork of a room and for such use, the bottom is closed and provided with a central opening for passage of a tack or nail 12, as in the modification shown in Fig. 5, for securing the 20 inner member to the wall or woodwork.

If the projection of the fastener members on the inside of the fabric, as shown in Fig. 1, is found objectionable for any reason, they may be arranged to stand up from the outer surface 25 of the fabric, as in the modification shown in Fig. 6.

As the application and many important advantages of the invention will be apparent from the foregoing, further description of the same will 30 not be given.

Having described my invention, I claim:

A fastener for removably securing a button, ornament or the like to a fabric, comprising two members, provided with frustro-conical screw-thread interengaging means cooperating to receive a fabric interposed without puncture therebetween, one of the members having a flange at its upper end, and means integrally securing it to a button, ornament or the like. 40

ARTHUR ILLSCHE.
